[57] CLAIM

The ornamental design for a pitcher or similar article, substantially as shown and described.

DESCRIPTION

FIG. 1 is a top plan view of a pitcher or similar article showing my new design;

FIG. 2 is a front elevational view;

FIG. 3 is a bottom plan view thereof;

FIG. 4 is a side elevational view looking from either side of FIG. 2;

FIG. 5 is a front elevational view showing a modified form of my design shown in FIGS. 1-4; and

FIG. 6 is a side elevational view looking from either side of FIG. 5.

The rear view opposite the front view shown in FIGS. 2 and 5 is identical thereto, and the top view of the design shown in FIG. 5 is identical to the top view shown in FIG. 1.
